FATTY ACID PHENYLALKYLPIPERIDIDES
Francis E. Cislak, Indianapolis, Ind., assignor to Reilly
Tar & Chemical Corporation, Indianapolis, Ind., a cor-
poration of Indiana
No Drawing. Filed Apr. 5, 1965, Ser. No. 445,719
5 Claims. (Cl. 260—294.7)

This invention relates to a new composition of matter. More specifically, it relates to a new class of organic compounds.

The new class of organic compounds which are the subject matter of my present invention are fatty acid phenylalkylpiperidides. These new fatty acid phenylalkylpiperidides have the following general formula:

wherein R_1 , R_2 , and R_3 represent hydrogen or lower alkyl, they may be alike or they may be different, and R represents an alkyl or alkenyl radical having from 1 to 29 carbon atoms.

In general, my new class of compounds may be prepared by the interaction of a phenylalkylpiperidine with a carboxylic acid, a carboxylic acid ester, or a carboxylic acid chloride.

My fatty acid phenylalkylpiperidides are useful in the formulation of industrial paints. In the protection of steel tanks, bridge structures, pipe lines, etc., coal-tar pitch paints have been used for decades. In areas where sub-zero temperatures are encountered, it is necessary that the coal-tar pitch be flexible enough to avoid cracking the film at these sub-zero temperatures. Flexibility in coal-tar pitch is achieved by leaving more of the lower-boiling coal-tar oils in the pitch. While such pitch has the desired flexibility during the sub-zero exposure, it is not well adapted to the hot summer temperatures. The lower-boiling oils are volatilized by the sun during the summer with the result that a more brittle pitch must be able to go through the following winter. Because of their low volatility and their compatibility, my fatty acid phenylalkylpiperidides may be added to a coal-tar pitch free of lower-boiling oils and achieve a pitch that is flexible from winter to winter. I need use only 5 to 10% (based on the coal-tar pitch) of my fatty acid phenylalkylpiperidides to obtain a coal tar pitch suitable for the manufacture of coal-tar paints.

The fatty acid phenylalkylpiperidides having a higher molecular weight fatty acid radical may be used in printing inks to modify their tackiness; only minor amounts are required to obtain the desired result. The tack of printing inks is of great importance, particularly in process inks for color printing. Successful application of successive colors require that each color be more tacky than the color applied over it, in order that film rupture may occur in the top rather than in the bottom film.

Ordinary window putty is usually composed simply of a thick plastic paste of whiting (calcium carbonate) and linseed oil. The putty hardens and therefore is not satisfactory for sealing where there may be slight relative movement of the components. The addition of from 10 to 30% (based on the linseed oil) of my fatty acid phenyl-alkylpiperidides so modifies the putty that it may be used for sealing even though there may be some relative movement of the components.

My fatty acid phenylalkylpiperidides are useful as plasticizers. Because of their low volatility, they are useful in plasticizing polyvinylchloride used in high tempera-

2

ture wire insulation applications. Usually from 25 to 50 parts of plasticizer are used for each 100 parts of polyvinylchloride homopolymer.

The phenylalkylpiperidines used in carrying out my invention are made by the catalytic hydrogenation of phenylalkylpyridines.

The manner in which the compounds of my invention may be prepared is illustrated by the following examples. It is to be understood that these examples are given by way of illustration only and are not intended as a limitation upon my invention.

EXAMPLE 1

Stearic acid 4-phenylpropylpiperidide

25 Into a flask equipped with a stirrer and a condenser is placed 500 grams of methyl stearate. The ester is warmed to liquefy it. To the liquid methyl stearate there is added 186 grams of 4-phenylpropylpiperidine. While stirring the mixture, its temperature is gradually raised. A reaction occurs causing an evolution of methanol and the formation of the stearic acid 4-phenylpropylpiperidine. Heating 30 is continued, in the range of 150-175° C., until about 32 cc. of methanol has been collected. Then the excess methyl stearate is removed from the reaction mixture by distillation under vacuum. The residue remaining after the 35 methyl stearate has been distilled is a semi-pure stearic acid 4-phenylpropylpiperidine. If a lighter colored product is desired, the residue is distilled under high vacuum, about 0.5-1.0 mm. Hg; the product distills over at a temperature above about 250° C.

The piperidine is insoluble in water and alcohol; it is soluble in benzene.

EXAMPLE 2

Lauric acid 4-(1'-ethyl-3'-phenylpropyl)piperidide

The procedure of Example 1 is repeated with the exception that 500 grams of methyl laurate is used in place of the methyl stearate and 214 grams of 4-(1'-ethyl-3'-phenyl) propylpiperidine is used in place of the 186 grams of 4-phenylpropylpiperidine.

EXAMPLE 3

Acetic acid 2-phenylpropyl-5-ethylpiperide

70 Into a flask equipped with a stirrer and a reflux condenser are placed 600 grams of acetic anhydride and 214 grams of 2-phenylpropyl-5-ethylpiperidine, the latter is added slowly in small portions. After all of the piperidine has been added, the mixture is heated under reflux conditions for from about two hours to about five hours. Dur-

ing the refluxing the acetic anhydride acetylates the piperidine to form the piperidide, acetic acid is also formed. After the refluxing is concluded, the acetic acid formed and the unreacted acetic anhydride are removed by distillation. The residue, a quite pure acetyl 2-phenylpropyl-5-ethylpiperidide, is purified by distillation under vacuum.

EXAMPLE 4

*21-triacontenoic acid 4-phenylpropylpiperidide*Into a flask equipped with a stirrer and a condenser there is placed 473 grams of 21-triacontenoic acid (commonly called lumequeic). The acid is heated to about 80-90° and then there is added to it 186 grams of 4-phenylpropylpiperidine. Then the reaction mixture is heated slowly causing the temperature of the mixture to rise gradually. A reaction occurs causing an evolution of water and the formation of the lumequeic acid-4-phenylpropylpiperidide. When the temperature reaches about 150° C., it is maintained there until no more water is evolved (this usually takes about four to five hours). The product now in the flask is 21-triacontenoic acid-4-phenylpropylpiperidide.

EXAMPLE 5

*Linoleic acid 4-phenylpropylpiperidide*The procedure of Example 1 is repeated with the exception that 500 grams of the methyl ester of linoleic acid is used in place of the methyl stearate.

EXAMPLE 6

*Butyric acid 3-phenylpropylpiperidide*Into a flask equipped with a stirrer and a condenser there is placed 300 grams of butyryl chloride. The butyryl chloride is warmed to about 50° C. and then there is added with stirring 186 grams of 3-phenylpropylpiperidine and about 200 grams of finely ground sodium carbonate. The mixture is stirred continually. A reaction occurs whereby the butyric acid 3-phenylpropylpiperidide and sodium chloride are formed. The mixture is heated for about three hours. Then the excess butyryl chloride is removed by distillation. The piperidide is recovered from the residue by extraction with benzene.

EXAMPLE 7

*Oleic acid 4-phenylpropylpiperidide*The procedure of Example 1 is repeated with the exception that 500 grams of the methyl ester of oleic acid is used in place of the methyl stearate.

EXAMPLE 8

*Palmitic acid 4-phenylpropylpiperidide*The procedure of Example 1 is repeated with the exception that 500 grams of methyl palmitate is used in place of the methyl stearate.

EXAMPLE 9

*Propionic acid 4-phenylpropyl-2,6-dimethylpiperidide*The procedure of Example 3 is repeated save that 214 grams of 4-phenylpropyl-2,6-dimethylpiperidine is used in place of the 2-phenylpropyl-5-ethylpiperidide.

EXAMPLE 10

*Adipic acid-di-4-phenylpropylpiperidide*The procedure of Example 4 is repeated with the exception that 73 grams of adipic acid is used in place of the lumequeic acid.

EXAMPLE 11

*Terephthalic acid-di-4-phenylpropylpiperidide*The procedure of Example 1 is repeated with the exception that 92 grams of dimethylterephthalate is used in place of the methyl stearate.

In the examples above I have used individual fatty acids or their derivatives. Commercially it would be desirable to use the regular grades of commercially available fatty acids. Then I would obtain a mixture of piperidides but these are preferred commercially because of their lower cost.

If in place of the methyl laurate used in Example 2, I use the methyl ester of coconut fatty acids, I obtain a mixture of piperidides with the lauric acid one predominating but also present in significant amounts are the piperidides of myristic, palmitic, capric, and caprylic acids. Or I might use the coconut oil itself, distilling off under vacuum the glycerine as it is formed. I can use rape-seed oil, in which case the piperidide of erucic acid ($C_{21}H_{41}COOH$) will predominate in my mixture and ap-

preciable quantities of oleic acid and linoleic acid piperidides will be present.

I claim as my invention:

1. Phenylalkylpiperidides of the formula

wherein R₁, R₂, and R₃ are selected from the class consisting of hydrogen and lower alkyl, and R is selected from the class consisting of alkyl and alkenyl radicals having from 1 to 29 carbon atoms.

2. Stearic acid 4-phenylpropylpiperidide.
3. Lauric acid 4-phenylpropylpiperidide.
4. Linoleic acid 4-phenylpropylpiperidide.
5. Oleic acid 4-phenylpropylpiperidide.
